UNITED STATES PATENT OFFICE.

FRANK B. SCHUYLER, OF BERKELEY, AND JOSEPH F. RUSSELL, OF OAKLAND, CALIFORNIA, ASSIGNORS TO JOHNSON WASHER CO., OF EMERYVILLE, CALIFORNIA.

WASHING MACHINE.

Application filed November 3, 1924. Serial No. 747,497.

Our invention is an improved impeller for washing machines, and particularly for that type of washing machine in which the impeller is positioned adjacent the top thereof—that is, the drive shaft extending through the top, and thus actuating the impeller.

The object of our invention is to provide an impeller which will create a rapid circulation of water in the tub, thus causing the clothes to circulate and consequently will efficiently wash them.

Another object of this invention is to provide an impeller in which the inner ends 15 of the blade intersect to form a backing, thus forcing all the water outwardly and horizontally from the ends of said blade, and upwardly toward the center of the impeller. Our impeller is designed to operate 20 with the closed horizontal plate at substantially the surface of the water, with the blades extending downwardly to the water, thus none of the water circulated by the propeller will pass through this horizontal 25 plate.

Another object is to provide a tapered tub which assists the downward circulation of the water.

In the annexed drawing in which our invention is illustrated:

Figure 1 is a plan view of our impeller.

Figure 2 is a side view of the same.

Figure 3 is an enlarged fragmentary sectional view of our impeller.

Figure 4 is a perspective view of a washing machine with our impeller positioned therein, and with parts broken away to show the construction thereof.

Figure 5 is an enlarged fragmentary sectional view of the washing machine tub.

Figure 6 is a side view of a modified form of impeller.

Referring more particularly to the drawing, the washing machine 1 is provided with the usual cover 2, upon which suitable gearing 3 is positioned to drive the shaft 4 upon which our impeller 5 is mounted. The tub A is tapered inwardly towards the top thereof, and the sides are corrugated as shown at B in Figure 5, the object of which will be further described. The impeller 5 comprises a top plate 6, the edges 6' of which are bent downwardly to deflect the water, from which a plurality of blades 7 depend.

These blades are preferably four in num-

ber set 90° apart. The top 5 is not formed in a perfect circle, but the portions between the blades are cut away, as shown at 8, to further lighten the impeller, and thereby reduce the load upon the driving mechanism. 60 A socket 9 is formed in the center of the plate 6 in which the squared end of the shaft 4 extends, said shaft being secured to the impeller 5 by the coupling 10, which is suitably bolted to the top plate 6. A block 65 10a is pinned to the end of the shaft 4 by a pin 10b, which extends from the sides of said block, and is adapted to engage a shoulder 10c in the coupling 10 to prevent the withdrawal of said block and shaft. The 70 block 10a is squared and this serves to rotate the impeller 5. A socket 9 is adapted to receive the block 10a when the impeller 5 is moved upwardly, that is, a knot or bundle of clothes may be formed under the impeller, and in order not to tear or mutilate 75 said clothes the impeller may move upwardly away from them thus clearing itself therefrom. Also the block 10a is not rigidly mounted in the coupling 10, but may move 80 slightly therein, thus allowing the impeller 5 to tilt slightly whenever a bundle or knot of clothes appears on the outer edge thereof.

The inner ends of the blades 7 are slightly cut away, as shown at 11, said cut being a 85 gradual curvature so that the clothes will be momentarily caught upon the impeller, and thus impede this movement outwardly.

In operation, the water is thrown outwardly from the outer edge of the blades 7, 90 the solid center part preventing the passage of the water therethrough, the rapid oscillation of the impeller causing a rapid movement of the water outwardly therefrom, downwardly along the flared sides of the 95 tub, and thence upwardly towards said impeller, thus the clothes are drawn upwardly towards the center of the impeller, and are thrown outwardly following the movement of the water from the end of the blades 7. 100 The fact that the blades 7 extend to the center of the impeller 5 prevents the water from passing around the inner edge of said blades, and when the impeller is oscillated the water is compelled to move outwardly 105 from the end of the blades, thus causing a rapid circulation of the water outwardly from said impeller as well as upwardly thereto.

Also this outward movement of the water 110

carries the clothes along with it, and throws them against the corrugated surface of the tub A forming an abrasive action and thus more effectively cleaning the clothes. The 5 frustro conical shape of the tub also assists in this circulation of the water downwardly from the impeller, and upwardly towards the same at the center of the tub. This constant circulation thoroughly and efficiently 10 cleans the clothes.

Having described our invention, we claim:

1. An impeller for rotatable mounting in the top of a frustro-conical tub of a washing machine, comprising a flat imperforate top 15 plate with a down-turned peripheral edge, radially arranged blade members depending from said top plate inside of said down-turned edge; said blades intersecting at the impeller axial center and having their lower 20 edges recessed to form depressed portions at and about the axial center.
2. An impeller for rotatable mounting in the top of a frustro-conical tub of a washing machine, comprising a flat imperforate top 25 plate with a down-turned peripheral edge, radially arranged blade members depending from said top plate inside of said down-turned edge; said blades intersecting at the impeller axial center and having their lower

edges recessed to form depressed portions at 30 and about the axial center, a socket extending axially on said top plate, and a block in said socket adapted to reciprocably engage and support said socket; said block being adapted to be secured to impeller rotating 35 means of the washing machine.

3. An impeller for rotatable mounting in the top of a frustro-conical tub of a washing machine, comprising a flat imperforate top 40 plate with a down-turned peripheral edge, radially arranged blade members depending from said top plate inside of said down-turned edge; said blades intersecting at the impeller axial center and having their lower 45 edges recessed to form depressed portions at and about the axial center, a socket extending axially thru the top plate into the intersection of said blades, a block in said socket; and means secured to the upper face of the top plate for reciprocably securing said 50 block in said socket; said block being adapted to be secured to impeller rotating means of the washing machine.

In testimony whereof we affix our signatures.

FRANK B. SCHUYLER.
